United States Patent Office.

FREDERICK S. BARUS, OF NEW YORK, N. Y.

Letters Patent No. 92,564, dated July 13, 1869.

IMPROVEMENT IN LOW-WATER INDICATORS.

The Schedule referred to in these Letters Patent and making part of the same.

To all whom it may concern:

Be it known that I, FREDERICK S. BARUS, of the city, county, and State of New York, have invented a new and improved Low-Water Detector for Steam-Boilers; and I do hereby declare that the following is a full, clear, and exact description of the same, reference being had to the accompanying drawings, which form part of this specification, and in which—

Figure 1 represents a plan view of a low-water detector constructed according to my invention;

Figure 2, a similar view thereof, with the upper cap removed;

Figure 3 represents a vertical section of the apparatus, illustrating the interior of the same while the water in the boiler is at the proper stage; and

Figure 4 is a similar view of the apparatus, illustrating its operation when the water is at low stage.

Similar letters of reference indicate corresponding parts in the several figures.

This apparatus consists of an elevated chamber, kept filled, by the pressure of steam, with water from the boiler, while the water is at a proper level within the latter, and containing a bucket or open-mouthed vessel, in which water is trapped in such a manner, and which is so connected with the valve, providing for the escape of the steam, by which the lowness of the water is to be detected, that when the water has returned from the chamber to the boiler, on that in the boiler sinking below the desired level, the weight of the water in the said bucket will produce the opening of the said valve, and cause the lowness of water to be detected.

Referring to the accompanying drawings—

L represents a portion of a steam-boiler. On the top of this boiler, and securely attached thereto, is a receptacle or chamber, H.

Said cylinder or chamber H communicates with the interior of the boiler L, by means of pipes, D and K, in the manner as shown, and is provided, in its top, with an outlet-pipe, u, which may connect with an alarm-whistle, F, for sounding the same, or with a pipe, C, for operating a feed-pump, or with both.

At or near the lower end of the said outlet-pipe u is fitted a rotary valve-plug or cork, N, upon the projecting ends of which are arranged levers, S S, one of them being allowed to turn loosely thereon, while the other, fitting tightly, causes, by its turning, also the turning of the said cock.

Upon the long ends of the said levers S S are car-

ried weights, E E, for the purpose of closing the said cock, and keeping it closed until over-balanced by a heavier weight at the opposite ends of the said levers.

At the shorter ends of said levers S S are hinged connecting-rods r r.

To the opposite or lower ends of said connecting-rods r r, is suspended a cylindrically-formed bucket or open-mouthed receptacle, g, as shown in fig. 3, so that the depression or settling down of said receptacle from any cause will turn the levers S S on their pivots, and thereby open the cock N, as shown in fig. 4.

The lower end of the pipe D is made to extend downward within the boiler L, to a level with the water-line at which the alarm or signal is designed to be given, while the corresponding end of the pipe K is made to extend some little distance lower down, as shown, so that while the water is at the proper stage, as in fig. 3, it is forced, by the pressure of steam, up through the pipes D and K, filling the cylindrical chamber H, and the smaller receptacle or bucket g contained therein.

When the water in the boiler gets below the level of the lower end of the pipe D, the steam enters into said pipe, and forces the water contained in the chamber H back into the boiler, through the tube K, and supplies its place therein. The water contained in the smaller receptacle being still retained therein, causes the overbalancing of the weights E E, and the consequent opening of the cock N, as shown in fig. 4, whereupon an alarm is sounded by the whistle F, or motion given to the feed-pump, or both, as may be desired.

The inner receptacle or bucket g is or may be perforated at its bottom with an opening, f, for the purpose of allowing the gradual discharge of its contents, thereby providing for the ultimate over-balancing of the same by the weights E E, and the consequent closing of the cock N.

What I claim as my invention, and desire to secure by Letters Patent, is—

The combination and arrangement of the bucket g, vessel H, and weights E, whereby to operate the cock N, by means substantially as shown and described, and in the manner set forth.

F. S. BARUS.
